METHOD OF GENERATING VAPOR

Hans Gleichmann, Falkenhain, near Spandau, Germany, assignor to Siemens-Schuckertwerke Aktiengesellschaft, Berlin-Siemensstadt, near Berlin, Germany, a corporation of Germany

Application September 20, 1933, Serial No. 690,262
In Germany June 14, 1932

12 Claims. (Cl. 122—247)

This invention relates to improvements in the art of generating steam, particularly in steam generators of the type in which there is a forced passage of the operating medium therethrough. Experience has shown that great difficulties are experienced in the operation of forced flow multi-tubular steam generators due to the percentage of salt or salts in the water which is to be evaporated. To generally explain such difficulties the conditions prevailing in a drum boiler, i. e. a boiler with natural circulation, will be first explained.

In a drum boiler, there is a substantial water capacity and such capacity is maintained constant by hand or automatically by feed water regulators. The feed water, even though it is chemically prepared or obtained from evaporators, is never completely pure, but contains certain soluble impurities. As soon as the water evaporates these impurities (salts) remain in the water which has undergone no evaporation. The water contained in the boiler will consequently take up the salt constituents gradually. The ultimate result is that the water contains a substance in the nature of a lye which with time, constantly increases in strength and which may then be drained from time to time or continuously so as to thereby maintain the water contained in the boiler to a given concentration of the lye. In the case of a multi-tubular boiler with forced passage of the operating medium therethrough, there is no drum and therefore there is not the possibility of automatic cleaning. In contradistinction in such boilers the water is forced by a pump into the system at one end of the tube and leaves the other end of the tube as vapor. Evaporation occurs intermediate the ends of the tube. There is no substantial storage of water in the tubular system and accordingly there is not the possibility of draining off water gradually enriched with lye as in the case of the boilers of the drum type. The result is that in such boilers there is a zone on the inner tube walls which is not sufficiently supplied with water, and salts, as experiments have shown, deposit in this zone until the vapor has attained a given degree of superheat. So long as the number of heat units imparted per unit of heating surface of the tubes is small such deposit of salts may form a considerable layer without subjecting the tubes to the danger of being burnt. On the other hand the conditions are entirely different in cases where a great number of heat units per unit of heating surface is imparted to the tubes as is usual for in-

stance, with modern radiation boilers. With the latter types of boilers a relatively slight settling of salt in the tubes contributes to a comparatively rapid destruction of the tubes. Since it is not possible with tubular forced flow boilers to extract the salt-like impurities from the feed water, other methods and means must be resorted to for boilers of the type which employ a heating surface to which heat of high intensity per unit of surface is imparted, in order to counteract and minimize the effects of the settling of salt in the tubular system.

An object of the present invention resides in the provision of a novel method of converting an operating medium from the liquid state to a vapor state in a forced flow generator and in providing for the minimizing of salt deposit difficulties in such generation of vapor.

A further object of the present invention resides in the provision of a novel multiple stage heating method for generating vapor in which the heating effects are such that the dangers attendant upon salt deposits are minimized.

A further object of the present invention resides in the provision of a novel method of converting an operating medium from the liquid state to a vapor state in a forced flow generator and in providing for the minimizing of salt deposit difficulties in such generation of vapor.

A further object of the present invention resides in the provision of a novel multiple stage heating method for generating vapor in which heating effects are such that the dangers attendant upon salt deposits are minimized.

Further and other objects of the present invention will be hereinafter set forth in the accompanying specification and claims and shown in the drawing which shows by way of illustration a preferred embodiment and the principle thereof and what I now consider to be the best mode in which I have contemplated of applying that principle. Other embodiments of the invention employing the same or equivalent principle may be used and structural changes made as desired by those skilled in the art without departing from the present invention and within the spirit of the appended claims.

In accordance with my invention, I provide a generator having several stages of heat absorption including the stage of heating water to or near the temperature of vaporization followed by a stage of heat absorption in order to effect complete vaporization at substantially constant temperature, the latter stage being the zone in which the fluid is converted from liquid to vapor

or at least the final stage of said vaporization being accomplished within said zone. The combustion apparatus may include a radiant heating zone followed by a contact or convection heating zone or zones, through which gases in passing therethrough fall in temperature. I have found that the conversion of liquid into vapor should be completed in the boiler tubing located in the contact or convection space where the temperature is low enough to avoid injury on account of deposition of salts. Therefore, from a broad point of view, my invention comprehends any arrangement of forced flow type of boiler wherein the medium at the saturated temperature is converted to steam and evaporation is completed in the contact or convection portion of the heating space to avoid injury to the tubing on account of salt deposits.

In the improved boiler and in accordance with the preferred and specific method of the present invention, the heat absorbing surface in which the evaporation takes place is divided into two portions receiving different amounts of heat supply per unit of heating surface, i. e. the generator is divided into a heat absorbing surface portion to which heat of higher intensity is imparted and in which, computed with respect to the entire extent of the heat absorbing surface portion, the percentage of liquid exceeds the percentage of steam in the operating medium and into another heat absorbing surface portion to which heat of lower intensity is imparted and in which conversely the percentage of vapor exceeds the percentage of liquid. With such generator it has been proven also practicable to add to the heat absorbing surface portion to which heat of lower intensity is imparted also, the first portion of the superheater. This is preferably done because first slightly superheated steam may still contain a certain amount of water, and secondly because such arrangement provides—upon variation in load and upon the shifting of the zone of evaporation,—a sort of safety zone, which safety zone maintains the zone of evaporation within the zone of heat of lower intensity per unit of heating surface.

In the accompanying drawing:

Figure 1 illustrates diagrammatically, the conditions prevailing in a steam generator with sub-divided heating surfaces for the evaporation of the operating medium according to the present invention:

In Fig. 2 is shown a cross-section of a steam generator embodying features of the present invention.

Referring first to diagrammatic Fig. 1, three fundamental zones in a forced flow steam generator should first be taken into consideration, i. e. the pre-heating zone W, the zone of evaporation V and the zone of superheat U. In the zone of pre-heating, sensible heat is imparted to the operating medium. In the zone V the heat of evaporation is imparted thereto and in the zone U the superheat is imparted to such medium. On entering the zone V the operating medium is substantially 100% liquid and 0% steam, whereas on leaving such zone the medium comprises 100% steam (theoretically) and 0% liquid. The dangerous zone is denoted by the zone G. This is the zone in which the heating surface is no longer in contact with sufficient water so that salt depositing difficulties and effects must be taken into consideration. According to the present invention this zone is not supplied with heat of the relatively high intensity. This is accom-

plished preferably by subdividing the heat absorbing surface portion V into sections *a* and *b*. The section *a* of the heating surface is supplied with heat of relatively high intensity and the section *b* supplied with heat of relatively low intensity. While the specific method described herein preferably involves dividing the heat absorbing surface V into sections *a* and *b*, the section *a* being heated in the high intensity or radiant heat portion of the heating space and the section *b* being supplied with heat of relatively low intensity in the convection or contact portion of the heating space, it is to be understood that, so far as my invention is concerned, the means of applying heat in this way, although desirable, is not essential, my invention comprehending the arrangement of the preheating zone W, the zone of conversion V, and the zone of superheating U, whether the evaporation zone V is located partly in the radiant space and partly in the contact space or entirely in the latter, the only requirement being that at least the final evaporation and preferably a part of the superheating shall be completed in the contact or convection portion of the heating space so that salt deposit difficulties may be overcome. In computing the proportions of the heat absorbing surfaces for evaporating a certain amount of heating medium, the heat absorbing parts or sections are so proportioned with respect to each other and to the total extent of heat absorbing surface that the percentage of liquid exceeds the percentage of steam in the *a* section and conversely in the *b* section the percentage of steam exceeds the percentage of liquid. The dangerous zone G comprises, as shown in Fig. 1, not only the section *b* of the evaporating zone V, but also the section *c* which constitutes a part of the heat absorbing surface of the superheater. How much of the total surface should be of the *b* type to which heat of the relatively lower intensity should be imparted and how much should be of the *a* type to which heat of relatively higher intensity is to be imparted will depend upon the particular conditions upon which the steam generator is to operate. According to previous experience, the zone of sub-division of the two heat absorbing surface portions *a* and *b* may be shifted in the direction of progressive evaporation towards the steam side so that the *a* section may terminate and the *b* section commence at a point where the system contains heating medium which is about 10% liquid (note e Fig. 1). At this point there is approximately 90% steam in the tubular system. The exact point of sub-division of the heating surface between *a* and *b* is a matter to be ascertained for each generator. In some cases, the sub-division point may be shifted towards the steam side and in other cases it may be shifted towards the liquid side. The later shift of the sub-division point towards the liquid side will be convenient and preferable if the generator operating conditions are such that in operation there is a considerable variation, shift, or displacement of the evaporating zone V, as for instance, with variations of load, variations of feed water temperature and variations of furnace temperature and conditions. The superheating surface *c* and particularly its section which is to be supplied with heat of relatively low intensity due to possible water in the entering steam, may be determined in the same manner according to the operating conditions.

Referring now to Fig. 2, here is shown one and a preferred embodiment of a steam generator

which incorporates the features of the present invention.

The steam generator shown may be of a form in which the products of combustion are derived from pulverized coal. The pulverized coal is conveyed from a bunker 18 by a distributing feed screw 16 into the burner piping and finally discharged at the burner nozzle 12. The feed screw may be driven by a motor 13 and the speed of the motor and the rate of delivery of the pulverized coal may be varied by manipulating a rheostat 15. The air for supporting combustion may be introduced into the generator by means of a blower 16 which delivers the air through piping 17 to the burner nozzle 12. The blower has an inlet at 18 and preferably and usually the entering air is pre-heated in the customary manner. The blower 16 may be driven by a motor 19 and the speed of such motor may be varied and regulated by a rheostat 20. The combustion gases evolved from the pulverized fuel flame take the path shown by the arrows in Fig. 2, that is to say, they divide at the exit end of the furnace or combustion chamber 21 and the divided currents 22 and 23 pass through supplemental heat absorbing chambers 24 and 25. The gases leaving the top of these chambers again unite and are discharged from the generator by a propeller type of fan 26. This fan may be driven in any desired manner as by means of a motor 27 and the speed may be varied by means of a rheostat 28.

The medium to be heated such as water or other liquid is forced into the generator by means of a pump 29. The pump is driven by a suitable motor 30 provided with a rheostat 31 for controlling the speed of drive. From the pump the medium to be heated in the generator passes to and through a distributing header 32. Tubular heat absorbing elements of the generator are connected to such header 32. Such tubular elements extend into and preferably line the combustion chamber 21. This particular heat absorbing section of the generator is designated 33a and 34a and this is the section of the heat absorbing surface of the generator to which heat of relatively high intensity is imparted. The heat absorbing sections 33a and 34a receive high intensity heat principally by radiation and from such sections the medium to be heated passes to the tubular sections 35b and 36b which are disposed in the heat absorbing chambers 24 and 25 and arranged in such manner therein as to receive heat by convection from the hot gases. Such sections are substantially shielded from the effects of high intensity radiant heat. Each of these tubular sections 35b and 36b accordingly receives heat of relatively lower intensity and the heat load in the generator at this point is relatively less than the heat load in the combustion chamber 21 where heat transfer is effected to the tubular elements by highly intense radiant heat. After passing the sections 35b and 36b the medium to be heated passes through tubular heat absorbing sections 37c and 38c and from such sections it passes out of the generator at the collecting header 39. The sections 37c and 38c likewise receive high intensity radiant heat, being disposed within and preferably lining the walls of the combustion chamber 21.

The generator according to the present invention has its sections so proportioned and is operated in such a way that in the sections 33a and 34a the liquid content of the medium predominates over the steam content and high in-

tensity heat is received thereby so that this heat absorbing section operates with a relatively high heat load.

The operating medium in the sections 33a and 34a has heat of relatively high intensity applied thereto to raise its temperature to the evaporation point and then to effect the progressive transition or transformation of the medium from the liquid to the vapor state until a point is reached such that the medium is partially vaporized and the amount of vapor predominates over the residuum of liquid. Thus, it will be seen that the heating surface 33a, 34a may be used to effect heating of the liquid, if the temperature of liquid supplied thereto is below the saturation temperature, followed by progressive vaporization of the liquid, or such heating surface may be used entirely to effect progressive vaporization if liquid at saturation temperature is supplied thereto. The partially vaporized operating medium is supplied from the heating surface 33a, 34a to the heating surface 35b, 36b, the latter heating surface having heat of relatively lower intensity applied thereto so as to complete transformation of the operating medium into the vapor state and preferably to effect an initial stage of superheating. As hereinbefore pointed out, salts are deposited or concentrated in the heating surface during the latter part of conversion from the liquid to the vapor state and during the initial portion of superheating, this being the danger zone G referred to in connection with Fig. 1. Therefore, as the heating surface 35b, 36b is so arranged in the furnace as to be subject to heat of a relatively low intensity, it will be apparent that the danger zone, such as indicated in Fig. 1, may be located in such manner that the tubing will not be injured even though salts should be deposited therein. Applying the method of steam generation diagrammed in Fig. 1, the preheating stage W is effected to the extent required in the heating surface 33a, 34a or such heating may be effected in any other suitable heating surface. The stage of vaporization V is shown as comprising a first part a wherein the percentage of liquid predominates over the percentage of vapor and the second part b wherein the percentage of vapor predominates over the percentage of liquid. The first part, a, of the vaporization stage is effected in the radiant heating surface 33a, 34a. The latter part, b, of the vaporization stage and the initial part, c, of superheating, is effected in the heating surface 35b, 36b, subject to heat of relatively low intensity. The vapor, preferably superheated to some extent, is supplied from the heating surface 35b, 36b to the heating surface 37c, 38c wherein it is superheated. As illustrated, the latter heating surface is also preferably subject to heat of relatively high intensity.

The sections 37c and 38c constitute the superheating sections or portions and in these sections high intensity heat is imparted. Also the heat load in these sections is relatively high.

The generator may be so proportioned and operated as to effect some superheating in the 35b and 36b sections with the final high superheat secured in the sections 37c and 38c.

It will be understood that in practice the various heat absorbing sections will be so initially proportioned with respect to each other and with respect to the total extent of heat absorbing surface that the above described conditions will be carried out, viz. in the a section or sections the liquid content will pre-dominate over the vapor

content and in this stage heat will be supplied at high intensity and the heat load will be relatively high. In the b section or sections the vapor content will pre-dominate over the liquid content, the heating effect in this stage will be relatively lower and in this stage the heat load will be relatively low. In the c section or sections the medium will be entirely in the vapor state, the heat will be supplied at high intensity and the heat load will again be relatively high.

The generator, so proportioned, may then be operated in such a way as to maintain such operating conditions during the generation of steam and during the transition of the operating medium from a liquid to the vapor state and during the successive heating stages.

It will be understood that the generator should be so operated that the dangerous zone where evaporation occurs with the steam pre-dominating in content over the liquid will be maintained in the 35b and 36b sections.

In the operation of the generator difficulties attendant upon salt deposits may be minimized and obviated by properly initially designing the various sections and operating the generator to maintain the above described evaporating conditions.

In the generation of steam with the generator sections properly initially designed, the improved operating conditions may be maintained under various steam generating conditions by effecting merely a proper adjustment of the heat supply and of the feed water supply. The various rheostats provide for the making of these adjustments for different steam outputs, feed water temperatures, fuel conditions, etc.

From the foregoing, it will be apparent that I have devised a boiler of the forced flow type wherein difficulties on account of salt deposition are overcome, this being done by having at least that portion of the heat absorbing surface wherein vaporization of medium at the saturated temperature is completed, located in the contact or convection portion of the heating space which is at such a low gas temperature that the tubing will not be injured even though deposition of salts should occur. While I disclose herein a specific arrangement where the zone of vaporization of the medium at the saturated temperature is carried on both in the radiant and contact portions, it will be obvious that the general requirement of completion of vaporization of medium at the saturated temperature in the contact portion may be carried out in this way or the entire vaporization zone may be located in the contact or convection portion of the heating space subject to relatively low intensity heat.

The present application constitutes a continuation in part of my copending application, Serial No. 655,805, filed February 8, 1933, for Steam generators.

What I claim is:

1. The method of converting a liquid operating medium to superheated vapor in a forced flow tubular steam generator and of minimizing the difficulties due to salt deposits in the tubes in the evaporating zone, which comprises effecting the transition of the liquid to a superheated vapor in three stages, in one stage imparting heat of relatively high intensity to the liquid to raise the temperature thereof to the saturation point, in a second stage in applying heat to the liquid at saturated temperature to progressively change the latter to the vapor state, the latter part at least of the second stage being effected by heat

of such relatively low intensity that injury to tubing containing salt deposits will be minimized, and in a third stage effecting superheating of vapor received from the second stage by heat of higher intensity than that of said second stage.

2. The method of converting water serving as operating medium into steam in a forced-flow tubular steam generator and of minimizing difficulties due to salt deposits, which comprises having the medium absorb heat in a plurality of zones of heat absorption, in one zone, raising the temperature of the medium in the liquid state to the point of vaporization and, in a second zone, progressively increasing the vapor content and decreasing the liquid content of the medium at said temperature, the second zone including a first stage such that, at the end thereof, there is sufficient medium in the liquid state to carry salts in solution, and a second stage wherein the residuum of liquid with salts in solution is vaporized by heat of such relatively low intensity that injury to heating surface of said second stage having salts deposited thereon will be minimized.

3. The method of converting water serving as operating medium into steam in a forced-flow tubular steam generator operating at a pressure below the critical and of minimizing difficulties due to salt deposits incident to evaporation which comprises having the medium absorb heat in a plurality of zones of heat absorption, in one zone, raising the temperature of the medium in the liquid state to the point of vaporization and, in a second zone, progressively increasing the vapor content and decreasing the liquid content of the medium at said temperature, the second zone including a first part such that, at the end thereof, there is sufficient residuum of medium in the liquid state to carry salts in solution and a second part wherein said residuum of liquid is vaporized, heat of such relatively high intensity being used to effect said first zone of heat absorption that heating surface having salts deposited thereon would be injured, and the second part of the evaporation zone being effected by heat of such relatively low intensity that heating surface thereof having salts deposited thereon incident to vaporization will not be injured.

4. The method of converting water serving as operating medium into superheated steam in a forced-flow tubular steam generator and of minimizing difficulties due to salt deposits, which comprises having the medium absorb heat in a plurality of zones of heat absorption, in one zone, raising the temperature of the medium in the liquid state to the point of vaporization and, in a second zone, progressively increasing the vapor content and decreasing the liquid content of the medium at the vaporization temperature, the second zone including a first part such that, at the end thereof, there is sufficient residuum of medium in the liquid state to carry salts in solution and a second part wherein the residuum of liquid is vaporized, heat of such relatively high intensity being used to effect said first part of the second zone of heat absorption that heating surface thereof having salts deposited thereon would be injured and the second part of the second zone being effected by heat of such relatively low intensity that heating surface having salts deposited thereon will not be injured.

5. The method of converting water serving as operating medium into superheated steam in a forced-flow tubular steam generator and of minimizing difficulties due to salt deposits incident

to evaporation, which comprises having the medium absorb heat in a plurality of heat absorption zones, in one zone, raising the temperature of the medium in the liquid state to the point of vaporization and, in a second zone, progressively increasing the vapor content and decreasing the liquid content of the medium at said temperature, the second zone including a first part such that, at the end thereof, there is sufficient residuum 10 of medium in the liquid state to carry salts in solution and a second part wherein the residuum of liquid is vaporized, and, in a third zone of heat absorption, superheating the vapor, heat of such relatively high intensity being used to effect said first zone of heat absorption that heating surface thereof having salts deposited thereon would be injured and the second part of said second zone and the initial portion of the third zone being effected by heat of such relatively low intensity 20 that heating surface thereof having salts deposited thereon will not be injured.

6. The method of converting water serving as operating medium into superheated steam in a forced-flow tubular steam generator and of minimizing difficulties due to salt deposits, which comprises having the medium absorb heat in a plurality of zones of heat absorption, in one zone, raising the temperature of the medium in the liquid state to the point of vaporization, in a second zone, progressively increasing the vapor content and decreasing the liquid content of the medium at the vaporization temperature, and, in a third zone, effecting superheating of the vaporized medium, the second zone including a first 35 part such that, at the end thereof, there is sufficient residuum of medium in the liquid state to carry salts in solution and a second part wherein the residuum of liquid is vaporized, the vapor provided by the second zone being superheated in the third zone, heat of such relatively high intensity being used to effect said first and at least a portion of the third zones of heat absorption that heating surface thereof having salts deposited thereon would be injured and the second part of the second zone being effected by heat 40 of such relatively low intensity that heating surface having salts deposited thereon will not be injured.

7. The method of converting water serving as operating medium into superheated steam in a forced-flow tubular steam generator and of minimizing difficulties due to salt deposits, which comprises having the medium absorb heat in a plurality of zones of heat absorption, in one zone, raising the temperature of the medium in the liquid state to the point of vaporization, in a second zone, vaporizing the liquid in first and second stages, and, in a third zone, superheating the vapor in first and second stages, the medium being partially vaporized in the first stage of the second zone such that, at the end of such first stage, there is sufficient residuum of medium in the liquid state to carry salts in solution and the residuum of liquid being vaporized in the second stage of the second zone, heat of such relatively high intensity being used to effect said first zone and the first and second stages of said second and third zones, respectively, that heating surface thereof having salt deposits thereon would be injured and the second stage of said second zone and the first stage of the third zone being effected by heat of such relatively low intensity that heating surface thereof having salts deposited thereon will not be injured.

75 8. The method of converting water serving

as operating medium into steam in a forced-flow steam generator so as to minimize difficulties because of salts deposited incident to vaporization which comprises subjecting the medium to a first stage of heating to raise the temperature 5 thereof to the evaporation point and then to progressively effect transition of the medium from the liquid to the vapor state until the medium is partially vaporized so that, at the end of the first stage, there is sufficient medium in 10 the liquid state to carry salts in solution, the intensity of heat for the first stage being relatively so high that heating surface having salts deposited thereon would be injured, then withdrawing the medium in vapor and liquid states 15 from the first stage and away from effects of the high intensity heat, and then subjecting the medium to a second stage of heating to convert said residuum of medium in the liquid state into vapor, the intensity of heat of the second stage 20 being relatively so low that heating surface having salts deposited thereon will not be injured.

9. The method of converting water serving as operating medium into superheated steam in a forced-flow steam generator so as to minimize 25 difficulties on account of salts deposited on heating surface incident to completion of vaporization which comprises subjecting the medium to a first stage of heating to raise the temperature thereof to the evaporation point and then to progressively 30 effect transition of the medium from the liquid to the vapor state until the medium is partially vaporized so that, at the end of the first stage, there is sufficient medium in the liquid state to carry salts in solution, the intensity of heat of 35 the first stage being sufficiently high that heating surface having salts deposited thereon would be injured, then withdrawing medium in the vapor and liquid states from the first stage, and subjecting the withdrawn medium in the vapor and 40 liquid states to a second stage of heating in order to convert said residuum of medium in the liquid state into vapor and to superheat the vapor, the intensity of heat for the second stage 45 being sufficiently low that injury to heating surface having salts deposited thereon is minimized.

10. The method of converting water serving as operating medium into superheated steam in a forced-flow steam generator so as to minimize 50 difficulties due to salts deposited incident to vaporization and which comprises subjecting the medium to high intensity heat in a first stage of heating to raise the temperature of the medium to the evaporation point and then to progressively increase the vapor content and decrease 55 the liquid content until, at the end of the first stage, there is sufficient residuum of medium in the liquid state to carry salts in solution, withdrawing the medium in the vapor and liquid states from the effect of the relatively high 60 intensity heat, subjecting the withdrawn medium to relatively low intensity heat in a second stage of heating in order to convert said residuum of liquid into vapor, and superheating vapor received from the second stage by a third stage 65 of heating with heat at relatively high intensity.

11. The method of converting water serving as operating medium into steam in a forced-flow steam generator so as to minimize difficulties due to salts deposited on heating surface 70 incident to completion of vaporization which comprises subjecting the medium to a first stage of heating by the application of heat of relatively high intensity to raise the temperature of the medium to the evaporation point and then to 75

- progressively increase the vapor content and decrease the liquid content of the medium until, at the end of the first stage, there is sufficient medium in the liquid state to carry salts in solution, withdrawing the medium in the liquid and vapor states from the first stage and away from the effects of the relatively high intensity heat, subjecting the withdrawn liquid and vapor to a second stage of heating by the application of heat of relatively low heat intensity to effect vaporization of said residuum in the liquid state and superheating of the vapor, the intensity of heat of the second stage being sufficiently low that injury to heating surface having salts deposited thereon will be minimized, and subjecting the initially superheated vapor to a third stage of heating to effect superheating thereof.
12. The method of converting a liquid operat-

ing medium into vapor in tubular heating surface comprising supplying medium under pressure to the surface for passage therethrough, providing heat of such relatively high intensity that heating surface containing salt deposits would be injured thereby and heat of such relatively low intensity that heating surface containing salt deposits would not be injured thereby, applying the heat of relatively high and low intensities to the operating medium flowing through the heating surface to raise the temperature of such medium to the evaporation temperature and then to effect the progressive transition of the medium at that temperature from the liquid to the vapor state, the latter part at least of said step of transition being effected by the relatively low intensity heat.

HANS GLEICHMANN.
